UNITED STATES PATENT OFFICE

PABLO FRANCISCO NICOLINI, OF BUENOS AIRES, ARGENTINA

APPARATUS FOR PRODUCING PERFECT COMBUSTION

Application filed July 5, 1927, Serial No. 203,620, and in Argentina February 17, 1927.

My invention relates to a new apparatus for projecting pulverized petroleum by superheated steam pressure in the hearths of bakery and similar ovens, with a view to obtaining the heating of same. The invention is illustrated in its preferred form in the accompanying drawing, in which:

Fig. 1 is a general front view of the oven, in longitudinal section, indicating the boiler or intermediary, pipings, accessories, etc.

Fig. 2 is a horizontal sectional view thereof.

This new apparatus is composed of a boiler (1), embedded within the wall of the oven itself, which has a hearth with grates and ash-pan to which access is had through a door (2), a chimney (3), a feed pump (4), water gauges (5), manometer (6), safety valve (7), a dome for purifying steam (8), pipe where the steam is taken, which is continued by the conduit (9), provided with a valve (10), and which conduit (9) is then prolonged within the interior of the hearth in the form of a coil as shown in (11). The object of this coil is to superheat the steam which leaves the boiler or intermediary (1), which superheated steam descends later by the conduit (12) and reaches the revolving arm (13), and by the lower part the steam reaches and enters into the conduit (14), in other words, the pulverizing nozzle. In the lower part of the boiler is placed a conduit (15), through which runs the water from the boiler or intermediary and by gravitation penetrates into a flat coil which is found within the hearth (16) and again enters the conduit (17), the said coil circulating the water and steam to the boiler or intermediary (1). The object of this coil is to have a heating surface sufficient to generate the steam consumed by the burner, the nozzle (14). The resistance of the boiler or intermediary and the whole of its elements and accessories, may reach a pressure of as much as 200 lbs. per square inch, by which, having high pressure steam, and moreover, superheated, the pulverization of the petroleum is obtained with the minimum of steam and the maximum of velocity; as it can easily be understood that the moist steam extinguishes the fire, and consequently it is easy to comprehend that

the superheated steam at high pressure produces a white fire and a perfect working in the pulverization of the petroleum. Nevertheless the apparatus described can start working with a steam pressure of five lbs. per 55 square inch.

The petroleum is contained in the tank (18), and by gravitation descends to conduit (19) and passes through the jacketted pipe (20), which heats the petroleum as it descends to feed the nozzle (23), which has its corresponding stop cock (21).

The working of the apparatus for burning and pulverizing the petroleum is as follows:

Once the boiler or intermediary (1) is 65 filled up to a convenient level by means of the feed pump (4), we have water in conduit (15), coil (16) and conduit (17), and the hearth is then lit with wood, coal, etc., (this for the first time) until steam is produced 70 in the boiler. This production of steam may also be initiated by igniting fuel in the hearth of the oven and below the coil (16), in case of desiring to leave without effect the use of the hearth with grate and ash-pan behind door (2), and once steam is obtained it passes through the dome (8) and into the conduit (9), which is provided with the principal steam valve (10), and opening this it passes into the superheater (11), and from there 75 the superheated steam descends to the conduit (12) and reaches the revolving arm (13), by means of which it reaches the pulverizing nozzle (14). For regulating the exit of this steam, there is a valve (24), or say in the 80 lower part of the pulverizing burner, and in the higher part is found the conduit (23) from where the petroleum that descends from conduit (19) issues, and once the valve (21) is open, the passage of the petroleum 85 is regulated by the valve (22) which allows the passage of the petroleum, which is then pulverized by the superheated steam under pressure, which issues from the nozzle (14), convergent with the exit of the petroleum 90 nozzle (23). In this state the petroleum is ignited in long flames, the power of which is graduated by means of the entrance of petroleum and the quantity of steam which 95 may be necessary for normal working, and 100

which consumption of steam is produced by means of the coil (16), and the consumption of water produced by the working of the burner, or in other words, the feed, is effected by means of the feed pump (4). These nozzles are mounted in an articulated manner on a revolving arm (13), on which the nozzle can revolve in order to enter and leave the hearth; the valve (26) is co-related with a pipe which reaches within the oven, to introduce steam in a direct manner, and by means of which steam is supplied to the oven at the moment of the baking of the bread.

The merit of my invention consists in the placing of the boiler or intermediary embedded in the wall of the oven itself, and even in its interior part, to maintain in the apparatus a direct and permanent heating, as the temperature of the oven varies between 150 and 170 degrees centigrade. This point (the embedding of the boiler in the wall), is what precisely forms the principal motive of my invention, by means of which a permanent steam pressure is obtained, and once the apparatus is put in movement, it is by means of the coil (16) that the steam consumed by the burner is generated, and when it is desired to feed the boiler or intermediary, this is effected by means of the pump (4); this feeding may be carried out in many different manners, by means of a float (25), a pump coupled to an electric motor, an injector of the usual type, or by means of an arrangement whereby the water will by gravitation enter into the boiler or intermediary.

Having described the nature of my invention, and the manner in which it should be carried out in practice, I declare as my exclusive right the following claim:

40 In an oven construction for bakeries using hydrocarbon burners, including its oven wall and arch, a steam boiler including a furnace embedded between the wall and the arch masonry of the oven, an auxiliary steam and 45 water circulating means located within the confines of the masonry and connected to said boiler for maintaining the steam pressure in said boiler constant by the heat absorbed by said masonry after the extinguishing of said burners.

In testimony whereof I affix my signature.
PABLO FRANCISCO NICOLINI.
